Patented May 16, 1967

207,639

CASING FOR A COMPUTER CONSOLE

Leslie R. Walstrom, 16823 Excelsior Blvd.,
Minnetonka, Minn. 55343

Filed Sept. 27, 1965, Ser. No. 87,181

Term of patent 14 years

(Cl. D26—5)

FIG. 1

FIG. 2

FIG. 3

FIG. 1 is a front perspective view of a casing for a computer console, showing my new design;

FIG. 2 is a front elevation view thereof; and

FIG. 3 is a left-side elevational view thereof.

The right side of the casing, not shown, is a mirror image of the left side; while the rear thereof is plain and unornamented.

I claim:

The ornamental design for a casing for a computer console, as shown and described.
